UNITED STATES PATENT OFFICE

159,342

VACUUM CONDENSER

Jo Emmett Jennings, San Jose, Calif., assignor to
Jennings Radio Mfg. Co., San Jose, Calif., a
copartnership

Application June 29, 1945, Serial No. 120,399

Term of patent 14 years

(Cl. D26—8)

To all whom it may concern:

Be it known that I, Jo Emmett Jennings, a citizen of the United States of America and resident of San Jose, county of Santa Clara, State of California, have invented a new, original, and ornamental Design for a Vacuum Condenser, of which the following is a specification, reference being had to the accompanying drawing, forming part thereof.

Referring to the drawing:

Figure 1 of the drawing is a perspective view of the vacuum condenser, showing my new design from one side and Figure 2 is a perspective view showing the design from the opposite side.

I claim:

The ornamental design for a vacuum condenser, substantially as shown.

JO EMMETT JENNINGS.
